CLAIM

The ornamental design for a computer keyboard software key guide holder, as shown and described.

DESCRIPTION

FIG. 1 is a perspective view of a computer keyboard software key guide holder showing my new design the computer terminal, key guide, and hands are shown in broken lines for illustrative purposes only and form no part of the claimed design;

FIG. 2 is a right end elevational view thereof, the left end elevational view being a mirror image thereof;

FIG. 3 is an elevational view thereof as seen in the direction of lines 3—3 in FIG. 2, the key guide is shown in broken lines for illustrative purposes only and forms no part of the claimed design;

FIG. 4 is a top plan view thereof;

FIG. 5 is a front elevational view thereof;

FIG. 6 is a rear elevational view thereof;

FIG. 7 is a bottom plan view thereof.
